LIQUID METERING PUMP

Le Roy A. Prescott, Lyncott, Mich., assignor to
 Service Station Equipment Company, Con-
 shohocken, Pa., a corporation of Delaware

Application January 22, 1932, Serial No. 588,042

2 Claims. (Cl. 221—95)

My invention is particularly applicable to pumps for dispensation of viscous liquids such as lubricating greases and including a portable container from which the liquid is elevated by a 5 pump comprising a reciprocating piston operatively connected with a rotary crank. The grease is thus progressed step by step through a flow meter including a rotary index pointer which traverses a circular graduated scale. Ordinarily, 10 the intermittent reciprocation of the pump piston permits the formation of bubbles and pockets of air in the grease elevated from the container which cause a false manifestation of the amount of grease dispensed through the meter if the air 15 is allowed to remain thus occluded in the stream of grease forced through the meter.

Therefore, the principal object and effect of my invention is to provide simple and efficient means for eliminating the air from the grease during its 20 passage from the pump to the meter so that the meter shall accurately manifest only the actual volume of grease dispensed. As hereinafter described, my improved air releasing means includes a bypass conduit extending from the upper portion 25 of the passageway between the pump and the meter back into the container aside from the pump. The construction and arrangement are such that the air is squeezed from the stream of grease in said passageway, at the region of said 30 bypass conduit and escapes from said passageway back into the container, accompanied by a comparatively small amount of grease, leaving the passageway fully charged with a solid stream of grease from the region of said bypass to the 35 meter.

It is characteristic of the form of my invention chosen for illustration that the air release bypass is embodied in a single casting which forms the head of the pump structure projecting from the 40 grease container and carried by a cover for the latter; said casting being provided with a handle by which the whole apparatus is readily portable.

My invention includes the various novel features of construction and arrangement herein- 45 after more definitely specified.

In said drawings; Fig. I is a perspective view of 50 a liquid metering pump conveniently embodying my invention.

Fig. II is a plan view of said pump.

Fig. III is a vertical sectional view of said pump taken on the line III, III, in Fig. I in the direction of the arrows on said line.

In said figures; 1 is the liquid container conveniently formed as a cone of sheet metal having 55 its truncated apex tightly fitted in the annular

base frame 2 having four feet 3. Said container has the cover 5 also conveniently formed of sheet metal with its downwardly turned flange 6 permanently engaging the upper edge of said container 1. Said cover 5 has the liquid inlet opening 5 7 which is normally closed by the lid 8 which is pivotally connected with said cover 5 at 9 and is adapted to be held in closed position by the screw 10 provided with the wing nut 11.

Said cover 5 carries, suspended in said container 1, the pump cylinder 12. Said cylinder has, at the lower end thereof, the intake foot 13 provided with the foot valve 14 which is in fact a check valve which opens inwardly to permit ingress of grease but closes to prevent egress of 15 grease from said pump cylinder 12. Said pump cylinder 12 is carried by the single casting 16 which forms a casing head for the pump projecting exterior to said container and having the handle 17 by which the whole structure is readily 20 portable. Said casing 16 has the annular flange 18 which is detachably rigidly connected with said container cover 5, conveniently by three bolts 19 extending through said flange and cover and secured by the nuts 20. 25

Said casing 16 has the laterally extending hollow arm 22 inclosing the liquid passageway 23, which is connected by the pipe nipple 24 with the casing 25 of the flow meter having the liquid discharge outlet 26 connected by the flexible hose 27 30 with the liquid dispensing nozzle 28. It is to be particularly noted that said meter being thus directly connected with said casing head 16 for the pump is solely supported by said casing so that the entire pump and its appurtenances may be 35 assembled in connection with said casing 16 independently of the lid 5 for said liquid container 1, thus materially lessening the cost of production of my apparatus as compared with apparatus of the prior art in which the meter is attached to 40 and supported by the lid of the container independently of the pump, thus necessitating the employment of pipe fittings including a union for connecting the pump and meter.

Said flow meter casing 25 contains a rotary 45 member which is displaced by the flow of liquid therethrough and operatively connected with the shaft 30 carrying the index pointer 31 which is adapted to traverse a circular series of graduations in the indicator casing 33 to manifest the 50 volume of liquid dispensed through said meter.

Said pump head casing 16 has the journal bearing 34 for the inner end of the crank shaft 35 which is also journaled in the stuffing box bearing 36 and is provided with the crank lever 37 at 55

- its outer end having the handle 38 by which it may be conveniently rotated. Said shaft 35 has the gear 39 between its bearings in mesh with the reciprocatory rack bar 40 which is mounted to 5 reciprocate in said casing 16 in engagement with the slide bearing 41; which is shown in dotted lines in Fig. II on the side of said rack opposite to said gear 39 and which is formed in said casting 16 upon the side of the latter which is cut 10 away in Fig. III. The upper limit of the movement of said rack is determined by the axial adjustment of the stop screw 42 which is in screw threaded engagement with the top of said casing 16 and held in adjusted position by the nut 43. 15 Such adjustable means permits the operator to precisely predetermine the volume of liquid taken into the pump cylinder 12 and dispensed therefrom at each stroke of said rack limited by said stop screw.
- 20 Said rack 40 is rigidly connected with the piston rod 45 which carries the piston 46 which is mounted to reciprocate in liquid tight relation with said pump cylinder 12 but has the liquid ports 47 extending through it controlled by the 25 check valve 48 which works in opposition to the check valve 14.
- The arrangement above described is such that when said crank shaft 35 is turned, drawing said rack 40 upwardly, said piston valve 48 is closed 30 but said foot valve 14 is opened to permit grease to be drawn into the cylinder 12 from the container 1. However, when said shaft 35 is turned to thrust said rack 40 downwardly; said foot valve 14 is closed by the back pressure of grease above 35 it and said piston valve 48 opened to permit the grease between the two valves to flow through the ports 47 in the piston to the space in the cylinder 12 above said piston. Such reciprocation of the rack 40 quickly fills the space above said piston 40, in the cylinder 12, casing 16, and parts in communication therewith, with grease having more or less air occluded therein in bubbles and pockets. However, the continued operation of 45 said crank, as above described, so compresses the grease in the passageway 23 in the arm 22 as to squeeze the air out of it and discharge the air back into the container through the bypass conduit 50 which extends from the upper portion of said passageway 23 downwardly in communication 50 with the interior of said container 1 aside from the pump cylinder 12. Consequently, only a solid stream of liquid is discharged by the pump through the nipple 24 into the flow meter casing 25; so that the meter manifests only the actual 55 amount of liquid dispensed therethrough.
- It may be observed, that the elimination of air, or other gas, from the stream of liquid propelled by the pump is thus effected after the liquid has been discharged from the pump cylinder, but entirely within said pump casing head 16 and before 60 said stream enters the flow meter, so that said gas escape conduit is entirely independent of said meter, and that such elimination is effected without the interposition of any flow retarding valve 65 between the pump piston and the discharge opening from the pump cylinder.
- Such elimination of gas from the stream of liquid is automatically effected by the pressure of the liquid necessary to dispense it; the release of the gas from the voids in the stream of liquid being effected by breaking the stream of liquid 70 against the obstruction in the confined passageway 23 which is afforded by the gas escape conduit 50 which extends transversely to the stream of liquid in said passageway and is entirely in-

closed and secluded in said casing 16; the pressure upon the liquid to dispense it serving to also force the liquid out through said obstruction.

Therefore, I do not desire to limit myself to the precise details of construction and arrangement herein set forth, as it is obvious that various modifications may be made therein without departing from the essential features of my invention, as defined in the appended claims.

I claim:

1. In liquid dispensing apparatus, the combination with a container for a supply of liquid; of a removable lid for said container; a pump cylinder having a valved pump piston therein and a check valve at the bottom thereof; a single hollow casting, forming a pump casing head, rigidly but detachably secured on said lid and connected with the top of said cylinder suspending the latter in said container, from said lid, in spaced relation with the bottom of said container; a slide bearing in said casing, parallel with the axis of said cylinder; shaft bearings in said casing upon opposite sides of said slide bearing, and in coaxial relation with an axis transverse to the axis of said cylinder; a gear rack mounted to reciprocate in said slide bearing parallel with the axis of said cylinder and operatively connected with said piston; a gear in engagement with said rack; a shaft for said gear, journaled in said shaft bearings; a crank on said shaft, exterior to said casing; whereby said rack may be reciprocated to reciprocate said piston; a flow meter supported by said casing; a liquid passageway formed by and secluded in said casing, extending in communication with the interior of said cylinder and said flow meter; a gas escape conduit, extending parallel with the axis of said cylinder, within said passageway in said casing and supported at its lower end in said casing, in communication at its lower end with the interior of said liquid container; said gas escape conduit being entirely secluded in said pump casing head and forming an obstruction in said passageway for breaking the stream of liquid and releasing the gas therefrom; whereby said gas escape conduit is rendered entirely independent of said meter and air and other gases are automatically eliminated from the stream of liquid entirely within said pump casing, merely by dispensing operation of said pump, and fraudulent operation of said meter is precluded.
2. In liquid dispensing apparatus, the combination with a container for a supply of liquid; of a removable lid for said container; a pump cylinder having a valve pump piston therein and a check valve at the bottom thereof; a single hollow casting, forming a pump casing head, rigidly secured on said lid and connected with the top of said cylinder suspending the latter in said container from said lid, in spaced relation with the bottom of said container; a slide bearing in said casing, parallel with the axis of said cylinder; shaft bearings in said casing upon opposite sides of said slide bearing, and in coaxial relation with an axis transverse to the axis of said cylinder; a gear rack mounted to reciprocate in said slide bearing parallel with the axis of said cylinder and operatively connected with said piston; a gear in engagement with said rack; a shaft for said gear, journaled in said shaft bearings; a crank on said shaft, exterior to said casing; whereby said rack may be reciprocated to reciprocate said piston; adjustable stop screw means in said casing in cooperative relation with the upper end of said rack; whereby the upper limit of the movement

of said rack and consequent volume of liquid taken into and dispensed from said pump cylinder at each stroke of the rack thus limited, may be variably predetermined; a flow meter supported by said casing, independently of said stop means; a liquid passageway formed by and secluded in said casing, extending in communication with the interior of said cylinder and said flow meter; a gas escape conduit, within said 10 passageway in said casing, and supported at its lower end in said casing, in communication at its lower end with the interior of said liquid con-

tainer; said gas escape conduit being entirely secluded in said pump casing head and forming an obstruction in said passageway for breaking the stream of liquid and releasing the gas therefrom; whereby said gas escape conduit is rendered entirely independent of said meter, and air and other gases are automatically eliminated from the stream of liquid entirely within said pump casing, merely by dispensing operation of said pump, and fraudulent operation of said meter is precluded. 10

LE ROY A. PRESCOTT.
